(57) **CLAIM**

The ornamental design for a firearm suppressor, as shown and described.

DESCRIPTION

FIG. 1 is a perspective view of the firearm suppressor;
FIG. 2 is a side elevational view of the firearm suppressor;
FIG. 3 is a rear elevation view showing the discharge end of the firearm suppressor; and,

FIG. 4 is a front elevation view of the muzzle end of the firearm suppressor.

The broken lines depict portions of the firearm suppressor that form no part of the claimed design.
